CLAIM

The ornamental design for a storage container, as shown and described.

DESCRIPTION

FIG. 1 is a top front right perspective view of a storage container, showing my new design;
FIG. 2 is a bottom front right perspective view thereof;
FIG. 3 is a front elevation view thereof, with the rear elevation view being an identical image thereof;
FIG. 4 is a right side elevation view thereof, with the left side elevation view being an identical image thereof;
FIG. 5 is a top plan view thereof; and,
FIG. 6 is a bottom plan view thereof.
The broken lines represent the boundaries of the claim and form no part thereof.

1 Claim, 4 Drawing Sheets(56)
